UNITED STATES PATENT OFFICE

2,298,701

ELECTRIC MOTOR

Emanuel Kalish, New York, N. Y.

Application August 23, 1941, Serial No. 408,061

2 Claims. (Cl. 172—126)

This invention relates to electrically actuated hammers comprising a lifting solenoid and a centrally positioned plunger adapted to be raised within the lifting solenoid for effecting the strokes of the plunger or hammer.

An object of this invention is to provide a vertically mounted solenoid and a plunger lifted thereby in combination with a switch comprising a vibratory contact carrier for breaking the electric circuit to the solenoid, and means for augmenting the downward movements of the hammer due to resilient restoring actions.

Another object of this invention resides in the application of the device to the operation of a drum having a padded drum beater and spring means whereby the beater has flexible contact with the drum to prevent damage to the drum.

Another object of this invention resides in the provision of an electrically actuated hammer of this nature which is simple in construction, inexpensive to manufacture, efficient and reliable in its operation, and otherwise well adapted to the purpose for which it is designed.

With the above and other objects in view, the invention will be hereinafter more particularly described and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a side elevation of the electric hammer, partly broken away to show the interior of the solenoid.

Figure 2 is a side elevation of the device, showing its application in the operation of a drum, and means whereby the drum beater is resiliently secured to the lower end of the plunger and has flexible contact with the drum to prevent damage thereto.

In the illustrated embodiment of the invention the numeral 10 indicates an electric hammer comprising a hollow spool 11 which may be made of wood, and having a helical coil of wire 12 of uniform diameter and of cylindrical form, the ends of the wire being connected with a source of electric current 13.

A movable contact arm 14 having a downwardly and inwardly curved free end is hingedly mounted on a pin 15 in a bracket 16 and carries a contact screw 17. The lower end of the screw 17 engages a fixed contact 18 secured to the upper flange 19 of the spool 11.

A cylindrical soft iron core or plunger 20 is slidably mounted in the interior of the solenoid and when the coil of wire 12 is energized, a lifting effect is created upon the core or plunger 5 whereby its upper end passes above the flange 19 and forces the movable contact arm 14 in an upward direction and the contact screw 17 away from the fixed contact 18 and breaks the circuit.

An angularly shaped spring 21 is secured to 10 the upper flange 19 with its free end forming a resilient stop or infringement receiving cushion for resiliently restraining the upward movement of the movable contact arm 14. It will thus be seen that when the plunger 20 is lifted upwardly, 15 the movable contact arm 14 will forcibly contact and displace the spring 21, resulting in a recoil and downward pressure against the upper end of the plunger whereby the spring 21 augments the force of gravity in driving the plunger downward.

A plate 22 is secured to the lower face of the lower flange 23 of the spool 11 and serves as a stop for a pin 24 passing through the plunger and limits the downward movements of the plunger.

Figure 2 shows the application of the electric hammer 10 for beating a drum 25. The electric hammer is secured to a bracket 26 having a base 27 on which the drum is mounted. The lower flange 23 of the spool 11 is fixed to the bracket by bolts 28.

A drum beater 30 is resiliently secured to the lower end of the plunger 20 by a coil spring 31 mounted in frictional engagement on the plunger and having its upper end 32 passing 35 through a transverse aperture in the plunger.

The lower end 33 of the coil spring 31 passes through a transverse aperture in a cylindrical extension 34 at the upper end of the drum beater 30. The extension 34 is in frictional slidable engagement in a cylindrical aperture lengthwise of the lower end of the plunger.

When the plunger 20 is lifted by the coil 12, the movable contact 17 is raised away from the fixed contact 18, and the spring 21 is displaced. The recoil of the spring 21 again lowers the plunger and the contact 17 into contact with the fixed contact 18.

This action serves for repeatedly making and breaking the electric circuit which causes the plunger to vertically reciprocate. The length of the spring 31 is such as to bring the lower surface of the drum beater 30 a small distance below the upper surface of the drum 25. The spring 31 compresses slightly when the drum beater strikes the upper surface of the drum, and

stretches the said surface. The spring 31 thus serves as a means which provides flexible contact between the drum beater and the drum and prevents damage to the stretched upper surface of the drum.

In accordance with the patent statutes I have described and illustrated the preferred embodiment of my invention, but it will be understood that various changes and modifications can be made therein without departing from the spirit of the invention as defined by the appended claims.

I claim:

1. In a device of the character described, a hollow spool made of wood and having a solenoid coil wound thereon, a reciprocating plunger projecting into and being movable vertically under the influence of said coil, a fixed contact member secured to the upper surface of said spool, a spring pivotally mounted on said spool and carrying a contact member engageable with said fixed contact member, said spring being downwardly and inwardly curved at its free end and having the free end of said lower curved portion resting upon the upper end of said plunger, said plunger in its upward travel being adapted to move said curved spring upwardly, a spring fixed to said spool and being positioned in superposed and considerably spaced relation from said pivotally mounted spring and providing resilient means for impingement of said pivotally mounted spring, the free end of said impingement receiving spring and the curved free end of said pivotally mounted spring being jointly displaced and tensioned during the upward movement of said plunger, the displacement of the free ends of both springs causing a multiple recoil serving to restore said plunger to its normal lowermost position at an augmented rate, said plunger having a transverse extension at a point intermediate its ends, the lower surface of said spool having a

plate secured thereto and serving as a stop for said transverse extension for limiting the downward movements of said plunger.

2. In a device of the character described, a hollow spool made of wood and having a solenoid coil wound thereon, a reciprocating plunger projecting into and being movable vertically under the influence of said coil, a fixed contact member secured to the upper surface of said spool, a vibratory member pivotally mounted on said spool and carrying a contact member engageable with said fixed contact member, said vibratory member being downwardly and inwardly curved at its free end and having the free end of said lower curved portion resting upon the upper end of said plunger, said plunger in its upward travel being adapted to move said vibratory member upwardly, a spring fixed to said spool and being positioned in superposed and considerably spaced relation from said vibratory member and providing resilient means for impingement of said vibratory member, the free end of said impingement receiving spring and the curved free end of said vibratory member being jointly displaced and tensioned during the upward movement of said plunger, the displacement of said free ends of said curved vibratory member and said spring causing a multiple recoil serving to restore said plunger to its normal lowermost position at an augmented rate, said plunger having a transverse extension at a point intermediate its ends, the lower surface of said spool having a plate secured thereto and serving as a stop for said transverse extension for limiting the downward movement of said plunger, an abutment, said plunger comprising two relatively slid able members connected together by a coil spring to provide flexible contact between the lower end of said plunger and said abutment.

EMANUEL KALISH.
